RETRACTABLE GOAL POSTS

James E. Thompson, Oklahoma City, Okla.

Application October 17, 1957, Serial No. 690,787

6 Claims. (Cl. 273—55)

The present invention relates to improvements in goal posts for field games and has reference more particularly to goal post structure as used in football and games of similar character.

Football goal posts normally comprise a pair of spaced-apart uprights which support a horizontal cross piece or bar adjacent their upper end portions at opposing ends of a playing field. The entire structure is usually formed of wood. In recent years it has become an almost general practice particularly in college football games for the supporters of the winning team to tear down the goal posts at the termination of the game. The actions of these supporting fans is almost riotous in nature and frequently some of the participants are injured.

It is therefore the principal object of the present invention to provide a retractable football goal post structure whereby the same may be immediately retracted into the surface of the playing field at the termination of the contest.

Another object of this invention is to provide a goal post structure of this class which, when retracted into the surface of the earth, will have the uppermost end portions thereof substantially flush therewith which precludes the possibility of the unauthorized removal of any part of the structure.

Another object of the present invention is to provide a goal post structure of this character which, being substantially flush with the surface of the earth when retracted, permits the use of the playing field for activities other than football without interference of such games by upstanding goal posts.

Tearing down the goal posts by the action of enthusiastic spectators usually results in partial or complete destruction of the goal posts thus rendering them unfit for further service. This necessitates an added expense for the school or the home team in purchasing new goals and installing the same after each game.

It is therefore a further object of this invention to provide a goal post structure which may be repeatedly used and which needs little if any attention after the initial installation.

Still another object is to provide goal posts of this class which may be raised or lowered as desired from a predetermined remote control position.

The present invention accomplishes these and other objects by providing a pair of elongated spaced-apart vertically disposed supports adapted to be slidably received within co-operating sockets formed in the surface of an end portion of a playing field.

A gear rack is connected longitudinally to the inwardly disposed surface of each support. A cross bar extends between the supports and is slidably carried horizontally by the upper end portions of the gear racks. A recess is formed in the surface of the playing field between the supports for receiving the cross bar therein when the supports are fully retracted into the sockets. Reversible motor means within the recess is drivably connected to the

2

gear means for raising and lowering the supports and cross bar.

Other objects will be apparent from the following description when taken in conjunction with the accompanying single sheet of drawings, herein:

Figure 1 is a fragmentary cross sectional view, partly in elevation, illustrating the device in operating position;

Figure 2 is a horizontal cross sectional view taken substantially along line 2—2 of Fig. 1; and

Figure 3 is a fragmentary exploded perspective view of the upper end portion of one support and illustrating the manner of connecting the cross bar thereto.

Like characters of reference designate like parts in those figures of the drawings in which they occur.

15 In the drawings:

The reference numeral 10 indicates the device, as a whole, including a pair of spaced-apart vertically disposed supports 12 and 14 of a selected length which are adapted to be received within a pair of casings 16 and 18, respectively.

20 The casings 16 and 18 are sunk into or cast in drilled holes or sockets 20 and 22, respectively, formed in the end zone of a playing field. The casings are shown in the drawings as formed of metal but obviously they may be formed of any desirable material such as plastic

25 or concrete. The uppermost ends of the casings 16 and 18 are preferably substantially flush with the surface 24 of the playing field. The depth of the holes or sockets 20 and 22 is preferably such that the uppermost ends 26 and 28 of the respective supports 12 and 14 will be substantially flush with the surface 24 of the playing field when the supports are fully retracted thereinto. An elongated trench or recess 30 is formed in the surface of

30 the playing field between the upper end portions of the sockets 20 and 22. An elongated container or housing 32 is placed or formed within the recess 30 with the bottom or base 36 resting on the soil forming the bottom of the recess while the top or upper wall 38 of the housing is disposed below the surface 24 of the playing field for the purposes more fully explained hereinbelow. Obviously

35 the housing top may be removable or provided with a lid, not shown.

35 Elongated gear racks 40 and 42 are longitudinally secured to the inwardly disposed surface of the posts or supports 12 and 14, respectively, with the teeth of the

40 racks projecting inwardly in cooperating opposed relation. Each side of the upper end portion of each gear rack 40 and 42 is integrally joined to a pair of angular members 44 which extend laterally of the respective gear rack and includes flange portions 46 which project inwardly of

45 the posts in parallel spaced-apart relation. The angular members 44 thus form a U-shaped channel like extension on opposing sides of the upper end portion of the respective gear rack. Each of the flanges 46 is provided with a vertical slot 48 intermediate its ends for the purposes

50 which will presently be apparent.

55 A cross bar 50 formed of wood or other suitable material and substantially ovate in cross section extends between the supports 12 and 14. The opposing ends of the cross bar 50 are adapted to be received between the angular members 44 adjacent the gear rack teeth. The cross bar 50 is held in place between the angular members 44 by a pair of laterally extending ears 52 adjacent each of its ends. The ears 52 are adapted for

60 vertical sliding engagement within the slots 48. The angular members 44 extend downwardly from the upper ends of the posts a distance sufficient to place the cross bar 50 at a selected horizontal position below the uppermost ends of the supports as illustrated in Fig. 1. Cross sectionally the size of the cross bar is such that it substantially fills the remaining portion of the recess 30 above the top 38 of the housing when the supports are

65

70

retracted into the casings by the means more fully disclosed hereinbelow.

A pair of L-shaped hooks 49 are carried by opposing sides of each gear rack adjacent the lower end of the angular members 44 with the hooks projecting horizontally inward of the respective support. The free ends of the hooks 49 project vertically upward for insertion into co-operating perforations, not shown, in the lower surface of the cross bar 50 as an additional means for lifting the latter when the supports are raised.

A reversible electric motor 56 is mounted within the housing 32 medially its ends. The motor is provided with a pair of oppositely disposed drive shafts 58 and 60 which project horizontally outward from opposite sides of the motor toward the respective supports 12 and 14. Beveled gears 62 connected with the respective ends of the drive shafts 58 and 60 rotate a stub shaft 64 mounted on the base of the housing which in turn rotates a cogwheel 66 having the teeth thereof in mesh with the teeth of the respective gear racks 40 and 42. Suitable openings 68 are provided in the wall of the casings 16 and 18 adjacent the respective ends of the housing through which the cogwheels 66 project for contacting the gear rack teeth. Suitable wiring, not shown, connects the motor 56 to a source of electrical energy and control switches. Thus, when the motor 56 is run in one direction the supports 12 and 14 will be raised simultaneously to project upwardly out of the casings 14 and 16 while the angular members lift the cross bar 50 therewith. Actuation of the motor 56 in the opposite direction retracts the supports 12 and 14 into the casings and disposes the cross bar 50 within the recess 30 above the housing 32. During the retracting action of the supports the cross bar 50 contacts the top 38 of the housing before the upper end portions of the supports are fully retracted into the casings. It is at this point that the primary function of the slots 48 becomes evident since their sliding contact with the ears 52 permits the cross bar 50 to remain in position within the recess while the upper end portions of the supports are being fully retracted into the casings.

The ears 52 being slidably disposed within the slots 48 further provide a means for preventing rotation of either of the supports 12 and 14 relative to the respective casing and cogwheel. When the supports are fully retracted into the casings the upper ends 26 and 28 thereof and the upper surface of the cross bar 50 are substantially flush with the surface 24 of the playing field.

Obviously the invention is susceptible to some change or alteration without defeating its practicability, and I therefore do not wish to be confined to the preferred embodiment shown in the drawings and described herein, further than I am limited by the scope of the appended claims.

I claim:

1. A retractable goal post structure for an end zone of a playing field, the surface of said playing field having an elongated recess therein and having a pair of sockets extending vertically therebelow adjacent the respective ends of the recess, comprising: a casing within each said socket; a pair of vertically disposed spaced-apart parallel supports adapted to be slidably received within said respective casings; a pair of gear racks longitudinally secured in co-operative relation to the inwardly disposed surface of said supports, respectively, the upper end portion of said gear racks each having a pair of vertically extending angular members projecting inwardly of the supports in co-operating relation from opposing sides of the gear rack, said angular members each alignedly slotted vertically intermediate their ends; a cross bar extending between said supports and having its respective ends disposed between the respective said pairs of angular members, said cross bar being adapted to be received within the recess in the surface of said playing field; a

pair of ears carried by each respective end portion of said cross bar, said pairs of ears being slidably received within the respective slots in said angular members; a reversible motor within the recess in said field, said motor having a pair of opposing drive shafts projecting toward the respective said supports; and gear means carried by the free end of each said drive shaft and meshing with the teeth of each respective said gear rack, whereby actuation of said motor in one direction raises said supports and said cross bar upwardly and whereby actuation of said motor in the opposite direction retracts said supports into said casings and disposes said cross bar within the recess.

2. Structure as specified in claim 1 and a pair of L-shaped hooks carried by each respective said gear rack adjacent the lowermost end of said angular members, said hooks being adapted for engagement with the lowermost surface of the adjacent end portion of said cross bar for lifting the latter when said supports are raised.

3. A retractable goal post structure for an end zone of a playing field, the surface of said playing field having an elongated recess therein and having a pair of sockets extending vertically therebelow adjacent the respective ends of the recess, comprising: a pair of vertically disposed spaced-apart parallel supports adapted to be received within the sockets in said playing field; a pair of gear racks longitudinally secured in co-operative relation to the inwardly disposed surface of said supports, respectively, the upper end portion of said gear racks each having a pair of vertically extending angular guide members projecting inwardly of the supports in co-operating parallel relation from opposing sides of the gear rack, said angular guide members each alignedly slotted vertically intermediate their ends; a cross bar extending between said supports and having its respective ends disposed adjacent and between the respective said pairs of angular members, said cross bar being adapted to be received within the recess in the surface of said playing field; a pair of ears carried by each respective end portion of said cross bar, said pairs of ears being slidably received within the respective slots in said angular guide members; a reversible motor within the recess in said playing field, said motor having a pair of opposing drive shafts projecting toward the respective said supports; and gear means carried by the free end of each said drive shaft and meshing with the teeth of each respective said gear rack, whereby actuation of said motor in one direction raises said supports upward simultaneously to project out of said sockets while said angular members carries said cross bar therewith and whereby reversing the direction of said motor retracts said supports into said sockets and disposes said cross bar within the recess.

4. Structure as specified in claim 3 and a pair of L-shaped hooks carried by each respective said gear rack adjacent the lowermost end of said angular members, said hooks being adapted for engagement with the lowermost surface of the adjacent end portion of said cross bar for lifting the latter when said supports are raised.

5. A retractable goal post structure for an end zone of a playing field, the surface of said playing field having an elongated recess therein and having a pair of sockets extending vertically therebelow adjacent the respective ends of the recess, comprising: a casing within each said socket; a pair of vertically disposed spaced-apart parallel supports adapted to be slidably received within said respective casings; a pair of gear racks longitudinally secured in co-operative relation to the inwardly disposed surface of said supports, respectively, the upper end portion of said gear racks each having a pair of vertically extending angular flanges projecting inwardly of the supports to form a U-shaped channel, the legs of said U-shaped channels being alignedly slotted vertically intermediate their ends; a cross bar extending between said supports and having its respective ends disposed within the respective U-shaped channels, said cross bar being

adapted to be received within the recess in the surface of said playing field; a pair of laterally projecting ears carried by each end portion of said cross bar, said ears being slidably disposed within the respective slots in said U-shaped channels; an elongated housing horizontally disposed within the recess in said playing field, said horizontally disposed housing having open ends in communication with the respective casing in said sockets; a reversible motor within said horizontally disposed casing, said motor having a pair of opposing drive shafts projecting toward the respective said supports; and gear means carried by the free end of each said drive shaft and meshing with the teeth of each respective said gear rack.

10

6. Structure as specified in claim 5 and a pair of L-shaped hook members carried by each respective gear rack adjacent the lowermost end of said U-shaped channels, said hooks being adapted for engagement with the lowermost surface of the adjacent end portion of said cross bar for lifting the latter when said supports are raised.
